CONVERSION OF HYDROCARBON OILS

Original Filed Oct. 8, 1934

UNITED STATES PATENT OFFICE

2,112,376

CONVERSION OF HYDROCARBON OILS

Jacque C. Morrell, Chicago, Ill., assignor to Universal Oil Products Company, Chicago, Ill., a corporation of Delaware

Application October 8, 1934, Serial No. 747,268
Renewed February 4, 1936

6 Claims. (Cl. 196—48)

This invention particularly refers to an improved process for the fractional distillation of hydrocarbon oils of relatively wide boiling range, such as crude petroleum, for example, accompanied by the pyrolytic conversion, under independently controlled conditions, of selected relatively low-boiling and high-boiling fractions of the charging stock from the fractional distilling operation as well as further conversion within 5 the same system, of selected relatively low-boiling and high-boiling intermediate conversion products of the process.

The present invention offers a simple and unified system for the fractional distillation of hydrocarbon oils of relatively wide boiling range 15 accompanied by the selective conversion of relatively low-boiling and relatively high-boiling fractions of the charging stock as well as relatively low-boiling and high-boiling fractions of 20 the intermediate conversion products of the process. Selected relatively low-boiling fractions of the charging stock and selected relatively low-boiling fractions of the intermediate conversion products of the process are each subjected to independently controlled conversion conditions of 25 elevated temperature and superatmospheric pressure in a separate heating coil succeeded by a high-pressure reaction chamber, to which reaction chamber selected high-boiling fractions of 30 the charging stock and selected high-boiling fractions of the intermediate conversion products are directly supplied, whereby said relatively high-boiling fractions are heated by commingling with the highly heated relatively low-boiling fractions 35 and subjected, in the reaction chamber, to less severe conversion conditions than those to which the relatively low-boiling oils are subjected in the heating coils.

As a special feature of the present invention, 40 the overhead vaporous products resulting from the fractional distillation of the charging stock are preferably supplied, while still in vaporous state to the heating coil wherein they are subjected to conversion or reforming at relatively 45 high temperature, without being first subjected to condensation, which would result in a considerable loss of heat, and, in order to obviate the use of a vapor pump to pass the hot vaporous products from the topping operation through said 50 heating coil, the topping operation is preferably conducted at a pressure sufficiently higher than that employed in the heating coil to overcome the drop in pressure, due to friction, through the heating coil and succeeding portions of the system.

As another feature of the invention all or a portion of the heat required for fractional distillation of the charging stock may be supplied thereto by indirect heat exchange between the charging stock and the highly heated products 5 from the heating coil to which the low-boiling fractions resulting from said fractional distillation of the charging stock are supplied, and/or the heating coil to which the low-boiling fractions of the intermediate conversion products are 10 supplied. Aside from furnishing heat for the fractional distillation of the charging stock, this method of operation serves to cool the highly heated products from either or both of said heating coils sufficiently to prevent their excessive 15 further conversion. However, in any case, the highly heated products from both heating coils are cooled sufficiently to prevent their excessive further conversion in the reaction chamber by direct contact with the relatively high-boiling 20 fractions of the charging stock and of the intermediate conversion products and when desired, particularly in case a portion or all of the excess heat from both streams of highly heated products from the heating coils is required to effect 25 the desired degree of conversion of the higher boiling oils with which they are commingled in the reaction chamber, all or a portion of the heat required for fractional distillation of the charging stock may be derived from any other suitable 30 source.

In one specific embodiment the invention comprises subjecting hydrocarbon oil charging stock for the process, comprising an oil of relatively wide boiling range, to fractional distillation at 35 substantial superatmospheric pressure whereby to separate the same into relatively low-boiling fractions, comprising the overhead vaporous products, and relatively high-boiling fractions, comprising condensate or bottoms from the distilling operation, subjecting said low-boiling vaporous fractions to conversion conditions of elevated temperature and superatmospheric pressure in a heating coil, introducing the stream of highly heated products from said heating coil 40 into an enlarged reaction chamber, also maintained at superatmospheric pressure, and commingling therewith said high-boiling fractions of the charging stock, withdrawing both vaporous and liquid conversion products from the reaction 45 chamber, subjecting the latter to further vaporization at substantially reduced pressure, subjecting the vaporous conversion products, including those resulting from said further vaporization, to fractionation in a separate fractionating 50 55

zone, whereby their insufficiently converted components are condensed as reflux condensate and separated into selected relatively low-boiling and high-boiling fractions, subjecting fractionated vapors of the desired end-boiling point from said 5 separate fractionating zone to condensation, collecting and separating the resulting distillate and gas, returning said relatively high-boiling fractions at the reflux condensate to the reaction chamber for further conversion, subjecting 10 the relatively low-boiling fractions of the reflux condensate to independently controlled conversion conditions of elevated temperature and superatmospheric pressure in a separate heating coil and introducing heated products from said 15 separate heating coil into the reaction chamber.

The accompanying diagrammatic drawing illustrates one specific form of apparatus in which the invention may be practiced. It should be 20 noted that the optional methods of operation provided by the present invention are not equivalent but may be selected to suit requirements in order to give the process greater flexibility.

Referring to the drawing, hydrocarbon oil 25 charging stock for the process, preferably comprising an oil of relatively wide boiling range containing an appreciable quantity of both relatively low-boiling and relatively high-boiling components, such as crude petroleum, for example, is supplied through line 1 and valve 2 30 to pump 3 wherefrom it is fed through line 4, valve 5, heat exchanger 6, line 7 and valve 8 into distilling column 9, wherein it is subjected to appreciable vaporization and fractional distillation. In the particular case here illustrated 35 the heat required for fractional distillation of the charging stock may be supplied thereto in heat exchanger 6 by indirect contact and heat exchange between the charging stock and highly heated conversion products of the process, which are supplied to this zone, as well be later more fully described. It is however, also within the 40 scope of the present invention to employ a heating coil of any conventional form for the charging stock or to impart thereto all or a portion of the heat required for its fractional distillation in any other well known manner, not illustrated.

Distilling column 9 is preferably operated at 50 a substantially superatmospheric pressure in order to eliminate pumping of the overhead vaporous products from this zone which are supplied to cracking coil 12. In the case here illustrated, the charging stock is separated by fractional 55 distillation in column 9 into a selected overhead vaporous product of the desired end-boiling point and bottoms, which latter comprise components of the charging stock remaining unvaporized in column 9 as well as the components which are 60 condensed in this zone as reflux condensate. It is, of course, also within the scope of the invention, particularly in case the charging stock contains any desirable low-boiling, intermediate or high-boiling fractions which it is not desired to 65 subject to conversion, to separate the charging stock into more than two selected fractions and to withdraw said desirable components such as, for example, straight-run gasoline of good anti-knock value, lubricating oil, asphaltic material, etc., from the system by well known means, not illustrated in the drawing.

The selected low-boiling components of the 70 charging stock remaining uncondensed in column 9 are withdrawn, in the case here illustrated, 75 from the upper portion of this zone through line

10 to be supplied therefrom through valve 11 to conversion or reforming in heating coil 12.

When desired, a regulated portion of the overhead vaporous product from column 9 may be subjected to condensation, by well known means not illustrated, for the purpose of forming distillate which may be utilized as a refluxing medium in column 9 by recirculating said distillate to the upper portion of this zone, by well known means not illustrated. This is only one of the 10 many well known satisfactory methods which may be employed for assisting fractionation in column 9 and maintaining the desired vapor outlet temperature from this zone so as to control the end-boiling point of the materials subjected 15 to conversion in heating coil 12.

Heating coil 12 is located within a furnace 13 of any suitable form, by means of which the heat required for accomplishing the desired conversion of the low-boiling components of the charging stock is supplied thereto. Heating coil 12 is also preferably operated at a substantial superatmospheric pressure and the highly heated products are discharged from this zone through line 14 and may be directed, all or in part, through 25 line 15, valve 16, heat exchanger 6, line 17 and valve 18 into reaction chamber 20. The highly heated products from heating coil 12 passed, as illustrated, through heat exchanger 6, serve to supply to the charging stock all or a portion of 30 the heat required for its fractional distillation. When desired, all or a regulated portion of the stream of hot vaporous products from heating coil 12 may by-pass heat exchanger 6 by diverting the same from line 15 through valve 19 35 in line 14 into line 17 and thence to reaction chamber 20.

In case only a minor portion or none of the highly heated products from heating coil 12 are passed through heat exchanger 6 to be cooled 40 by indirect contact with the charging stock the heat contained in these products may be utilized to assist conversion of the relatively high-boiling oils supplied to reaction chamber 20, as will be later more fully described, in which case said 45 high-boiling oils serve to cool the highly heated products from heating coil 12 sufficiently to prevent their excessive further conversion in reaction chamber 20.

In the case here illustrated, the high-boiling 50 fractions of the charging stock withdrawn from the lower portion of column 9 through line 21 and valve 22 to pump 23 are fed therefrom through line 24, valve 25 and line 52 into reaction chamber 20.

Reaction chamber 20 is also preferably operated at a substantial superatmospheric pressure and, although not indicated in the drawing, is preferably insulated to prevent the excessive loss of heat therefrom by radiation so that conversion 60 of the various oils supplied to this zone, and particularly their vaporous components, may continue therein. The heat contained in the products from heating coil 12 and/or heating coil 45, which latter are also supplied to the reaction chamber, 65 as will be later more fully described, serving to heat the higher boiling oils supplied to this zone and effect their appreciable conversion therein at a temperature somewhat lower than the temperatures employed in the heating coils. In the particular case here illustrated both vaporous and liquid conversion products are withdrawn from the lower portion of chamber 20 through line 56 and valve 57 and are introduced into vaporizing chamber 26. It will be understood, however, 70 75

that, when desired, all or a regulated portion of the vaporous products may be separately withdrawn from chamber 20 at any desired point in this zone, by well known means not illustrated, in which case the separately withdrawn vapors may be supplied, all or in part, direct to fractionator 29 or may be introduced, all or in part, into vaporizing chamber 26 at any desired point in this zone, by well known means not shown in the drawing.

Chamber 26 is preferably operated at a substantially reduced pressure relative to that employed in the reaction chamber, by means of which further vaporization of the liquid conversion products supplied to this zone from reaction chamber 20 is accomplished. Residual liquid remaining unvaporized in chamber 26 may be withdrawn from the lower portion of this zone through line 58 and valve 59 to cooling and storage or to any desired further treatment. The vaporous products evolved in chamber 26 as well as any supplied to this zone from the reaction chamber may be directed through line 27 and valve 28 to fractionation in fractionator 29, together with any vaporous products which may be supplied, as previously mentioned, to fractionator 29 direct from reaction chamber 20.

The insufficiently converted components of the vaporous products supplied to fractionator 29, including their fractions boiling above the range of the desired final light distillate product of the process, as well as, when desired, regulated quantities of any selected high-boiling components of the desired light distillate product which are of inferior anti-knock value, are condensed in this zone as reflux condensate and, in accordance with the features of the present invention, are separated into selected relatively low-boiling and high-boiling fractions. The relatively low-boiling and high-boiling fractions of the reflux condensate are each subjected to further conversion within the system under different conversion conditions, as will be later more fully described.

Fractionated vapors of the desired end boiling point, preferably comprising materials within the boiling range of motor fuel of good anti-knock value, are withdrawn, together with uncondensable gas produced by the cracking operation, from the upper portion of fractionator 29 through line 30 and valve 31 to be subjected to condensation and cooling in condenser 32. The resulting distillate and gas passes through line 33 and valve 34 to collection and separation in receiver 35. Uncondensable gas may be released from the receiver through line 36 and valve 37 to absorption, storage or elsewhere, as desired. The distillate collected in receiver 35 may be withdrawn therefrom through line 38 and valve 39 to storage or to any desired further treatment. When desired, a regulated portion of the distillate collected in receiver 35 may be recirculated by well known means (not shown) to the upper portion of fractionator 29 to serve as a refluxing and cooling medium in this zone to assist fractionation of the vapors and to maintain the desired vapor outlet temperature from the fractionator.

Selected low boiling fractions of the reflux condensate formed in fractionator 29 may be withdrawn from any suitable intermediate point or plurality of points in this zone and supplied, for example, through line 40 and valve 41, to pump 42 by means of which they are fed through line 43 and valve 44 to further conversion in heating coil 45 under independently controlled conversion conditions. Sufficient heat is sup-

plied to the oil passing through heating coil 45 to bring it to the desired conversion temperature, preferably at a substantial superatmospheric pressure, by means of heat supplied from a furnace 46 of any suitable form and the heated products are discharged from heating coil 45 through line 47 and may pass through line 48 and valve 54 to be introduced, in the case here illustrated, through line 17 into reaction chamber 20, together with the products from heating coil 12. When desired, a regulated portion or all of the highly heated products from heating coil 45 may be utilized to furnish heat for fractional distillation of the charging stock by passing the same through valve 55 in line 47 and through line 15 into heat exchanger 6, from which the resulting partially cooled products pass through line 17 and valve 18 into reaction chamber 20. It will be understood, of course, that all or any desired portion of the heated products from either or both heating coils 12 and 45 may be utilized, as described, to supply heat to the charging stock while any remaining portion of either or both of these streams or all of either or both may by-pass heat exchanger 6. It will also be understood that the products from heating coils 12 and 45 may, when desired, be separately supplied to reaction chamber 20 each at any desired point in this zone, although well known provisions for accomplishing this are not shown in the drawing.

The high boiling fractions of the reflux condensate formed in fractionator 29 may be withdrawn, as illustrated, from the lower portion of this zone through line 49 and valve 50 to pump 51 by means of which they are returned through line 52 and valve 53 to reaction chamber 20. It will be understood that the relatively high boiling oils from column 9 and fractionator 29 may be supplied to reaction chamber 20, separately or in commingled state, at any desired point or plurality of points in this zone, although only one point of introduction is shown in the drawing.

In a process of the character illustrated and above described, the preferred range of operating conditions may be approximately as follows: The temperature to which the charging stock is subjected for the purpose of effecting its fractional distillation may range, for example, from 500 to 800° F., or thereabouts, depending upon its characteristics, the desired separation to be effected and upon the pressure employed in the fractional distilling stage of the process which pressure may range, for example, from 100 to 500 pounds, or thereabouts, per square inch. The conversion temperature employed at the outlet from the heating coil to which the low boiling fractions of the charging stock are supplied may range, for example, from 900 to 1100° F. and preferably a substantial superatmospheric pressure of the order of 200 to 500 pounds, or more, per square inch is employed at this point of the system although, when desired, lower pressures down to 100 pounds, or less, per square inch may be employed in this zone. The heating coil to which the selected relatively low boiling fractions of the intermediate conversion products of the process are supplied may employ an outlet conversion temperature ranging, for example, from 950 to 1050° F., preferably with a substantial superatmospheric pressure, measured at the outlet from the heating coil, of from 250 to 500 pounds, or more, per square inch. The reaction chamber is preferably operated at a substantial superatmospheric pressure of the order of 100 to 500 pounds, or thereabouts, per square inch, which pressure

may be substantially the same or somewhat lower than that employed in the heating coil utilizing the lowest pressure, in case different pressures are employed in the two heating coils. The vaporizing chamber is preferably operated at a substantially reduced pressure relative to that employed in the reaction chamber which may range, for example, from substantially atmospheric to 100 pounds, or thereabouts, per square inch superatmospheric. The pressure employed in the vaporizing chamber may be substantially equalized or somewhat reduced in the succeeding, fractionating, condensing and collecting portions of the system.

As a specific example of one of the many possible operations of the process of the present invention utilizing as charging stock a Montana crude of about 31.8° A. P. I. gravity containing approximately 5% of material boiling up to 215° F. and about 22% boiling up to 400° F. the crude charging stock is heated to a temperature of approximately 650° F. and is subjected to fractional distillation under a superatmospheric pressure of approximately 500 pounds per square inch. The overhead vaporous products from the fractional distilling operation comprising approximately 35% of the charging stock are subjected in a reforming coil to a conversion temperature of approximately 980° F. at a superatmospheric pressure substantially equalized with that in the fractional distilling stage. The stream of highly heated products from the reforming coil is utilized to furnish heat to the charging stock for its fractional distillation and is then introduced into a reaction chamber maintained at a superatmospheric pressure of approximately 350 pounds per square inch. The high boiling fractions of the charging stock, comprising bottoms from the fractional distilling stage of the process, are also supplied to the reaction chamber. Both vaporous and liquid products are withdrawn from the lower portion of the reaction chamber and introduced into a reduced pressure vaporizing chamber maintained at a superatmospheric pressure of approximately 45 pounds per square inch from which residual liquid is withdrawn while the vaporous products from this zone pass to the fractionator of the cracking system. Selected low-boiling fractions of the reflux condensate from the fractionator of the cracking system having a boiling range of approximately 320 to 600° F. but containing less than 5% of materials boiling below 400° F. are supplied to a separate heating coil wherein they are subjected to a conversion temperature of approximately 970° F. at a superatmospheric pressure of about 600 pounds per square inch and the heated products from this zone are discharged into the reaction chamber. The remaining higher boiling fractions of the reflux condensate from the fractionator of the cracking system are returned to the reaction chamber without further heating. This operation may produce, per barrel of charging stock, about 60% of 400° F. end-point motor fuel having an anti-knock value equivalent to an octane number of approximately 70 and about 26% of good quality residual liquid suitable as premium fuel oil, the remainder being chargeable, principally, to uncondensable gas.

I claim as my invention:

70 1. A process for the fractional distillation and conversion of hydrocarbon oils, which comprises subjecting hydrocarbon oil of relatively wide boiling range to fractional distillation at substantial superatmospheric pressure whereby it is separated into selected relatively low-boiling and

high-boiling fractions; withdrawing said low-boiling fractions from the fractional distilling stage in vaporous state and supplying the same, without intentional condensation thereof, to a heating coil wherein they are subjected to conversion conditions of elevated temperature and superatmospheric pressure, introducing the products from said heating coil into an enlarged reaction chamber also maintained at superatmospheric pressure and at a conversion temperature, 10 introducing said selected high-boiling fractions of the charging stock into said reaction chamber wherein they are subjected to conversion, withdrawing vaporous and liquid conversion products from the reaction chamber, subjecting the latter 15 to further vaporization at substantially reduced pressure, subjecting the vaporous conversion products of the process to fractionation, whereby their insufficiently converted components are condensed as reflux condensate and separated 20 into selected relatively low-boiling and high-boiling fractions, subjecting the fractionated vapors of the desired end-boiling point to condensation, collecting the resulting distillate, returning said high-boiling fractions of the reflux condensate 25 to the reaction chamber for further conversion, subjecting said selected low-boiling fractions of the reflux condensate to independently controlled conversion conditions of elevated temperature and superatmospheric pressure in a separate 30 heating coil and introducing the heated products from said separate heating coil into the reaction chamber.

2. A process of the character defined in claim 1, wherein regulated quantities of the highly 35 heated products from the first mentioned heating coil are utilized to supply heat for said fractional distillation of the charging stock, by indirect heat exchange therewith, prior to their introduction into the reaction chamber. 40

3. A process of the character defined in claim 1, wherein regulated quantities of the highly heated products from the last mentioned heating coil are utilized to supply heat for said fractional distillation of the charging stock, by indirect heat 45 exchange therewith, prior to their introduction into the reaction chamber.

4. A process of the character defined in claim 1, wherein regulated quantities of the highly heated products from both heating coils of the 50 system are utilized to supply heat for said fractional distillation of the charging stock, by indirect heat exchange therewith, prior to their introduction into the reaction chamber.

5. A hydrocarbon oil conversion process which 55 comprises fractionating the charging oil to form a relatively light fraction and a heavier fraction, simultaneously fractionating hydrocarbon vapors independently of the charging oil and separating a relatively light reflux condensate and a heavier 60 reflux condensate therefrom, passing said light fraction and said light reflux condensate through separate heating coils and subjecting the same therein to independently controlled cracking conditions of temperature and pressure, introducing the heated products from said coils into an enlarged reaction zone, introducing said heavier fraction and said heavier reflux condensate, without prior cracking thereof, to the reaction zone, separating the mixture formed in 70 the reaction zone into vapors and residue, fractionating the former as said hydrocarbon vapors, and finally condensing the fractionated vapors.

6. A hydrocarbon oil conversion process which 75 comprises fractionating the charging oil to form

5 a relatively light fraction and a heavier fraction, simultaneously fractionating hydrocarbon vapors and separating a relatively light reflux condensate and a heavier reflux condensate therefrom, passing said light fraction and said light reflux condensate through separate heating coils and subjecting the same therein to independently controlled cracking conditions of temperature and pressure, combining said heavier fraction
10 and said heavier reflux condensate, without prior

cracking thereof, with the heated products from said coils, passing the resultant mixture through an enlarged reaction zone maintained under cracking conditions of temperature and pressure, removing the mixture from the reaction zone and 5 reducing the pressure thereon to separate the same into vapors and residue, fractionating the former as said hydrocarbon vapors, and finally condensing the fractionated vapors.

JACQUE C. MORRELL. 10
